UNITED STATES PATENT OFFICE.

WILLIAM SALISBURY, OF WHEELING, VIRGINIA.

CATCH-BOLT.

Specification of Letters Patent No. 26,296, dated November 29, 1859.

To all whom it may concern:

Be it known that I, W. SALISBURY, of Wheeling, in the county of Ohio and State of Virginia, have invented a new and useful Improvement in Catch-Bolts; and I do hereby declare that the following is a full, clear, and exact description of the same, reference being had to the annexed drawings, making a part of this specification, in which—

Figure 1, is a face view of a lock applied to a door and provided with my invention. Figs. 2 and 3, are horizontal sections of the same, showing two different positions of the parts and taken in the same line x, x , Fig. 1.

Similar letters of reference indicate corresponding parts in the two figures.

This invention relates to an improvement in that class of catch bolts which are self-catching, that is to say, those which are provided with a basil at their outer ends and are forced inward by being shoved or drawn in contact with a proper nosing as the door is closed, a spring forcing the end of the bolt within the nosing.

The object of the invention is to avoid the friction and consequent wear attending the operation of the ordinary catch bolt, thereby rendering the device not only much more durable, but also causing the same to catch or operate with less noise and concussion than usual as the door is closed.

The invention consists in attaching to an ordinary catch bolt a lever arranged and applied substantially as hereinafter described, whereby the desired end is attained.

To enable those skilled in the art to fully understand and construct my invention I will proceed to describe it.

A, represents a lock which may be provided with a bolt placed within a case and arranged to be operated by a key in any of the known ways. B, is the catch bolt of the lock, which may also be arranged in the usual way so as to be drawn within the lock case by the turning of a knob when the door is to be opened. These parts being of usual construction do not require a minute description.

To the upper surface of the catch bolt B, a lever C, is attached by a pivot a . The lever C, is nearly equal in length to the bolt B, and is secured to the latter near its inner end the lever being allowed to turn or work freely on its pivot a . The outer part of the lever C, projects through the end of the lock case and has two curved surfaces b, c , one of which b , is precisely similar to

the usual basil d , of the catch bolt, the basil or curved surface b , however of the lever C, is rather farther inward than the basil d , of the catch bolt so that as the door is closed the basil b , of the lever will strike the nosing D, on the door frame instead of the basil d , as shown clearly in Fig. 2. The curved surface c , of the lever is concave and it bears against an upright bar or stem e , of the lock case formed by a slot f , which is made in the outer side of the case. The slot f , is made sufficiently large to allow the outer part of the lever to work through as the door closes.

The operation is as follows:—When the door is closed, the basil b , of the lever strikes the nosing D, and the concave curved surface c , of the lever is pressed against the bar or stem e , and the lever is thereby forced inward carrying with it the catch bolt B, the outer parts of both the lever and catch bolt being forced within the nosing by the usual spring when the door is closed, see Fig. 3. By the employment or use of the lever C, the catch bolt is shoved back within the lock case with far less friction than when the basil d , of said bolt is forced against the nosing, for in the latter case the catch bolt has no lateral yielding movement like the lever and consequently its side, at a point opposite its basil, is pressed, as the door is closed, directly against the bar or stem e , at right angles causing much friction and consequent wear, but, in the employment of the lever C, the curved surface c , readily slips over the bar or stem e , and a purchase is obtained which facilitates in a great degree the sliding back of the catch bolt.

The attachment of the lever C, to the catch bolt will not materially enhance the cost of the lock, the additional expense being quite inappreciable when compared with the advantages obtained by it. The invention is of course applicable to the catch bolt of locks or to simple catch bolts not connected with any lock.

Having thus described my invention what I claim as new and desire to secure by Letters Patent, is,

The employment or use of the lever C, combined and arranged with the catch bolt B, to operate substantially as and for the purpose set forth.

WM. SALISBURY.
